[57] ABSTRACT

In a keyboard electronic musical instrument having tone generators of frequency divider systems, every key is associated with and controls a plurality of tone keyers which respectively gate tone signals having frequencies being harmonically related with each other. The tone signal gated by one of the keyers is passed through a frequency shifter, while the tone signal gated by the rest of the keyers is not. Among the tone keyers, the above-mentioned one is a keyer for producing an attack signal, while the remainder are keyers for producing a normal lasting signal. Both signals, now being slightly out of harmonic relation, are mixed together and finally transduced into sound by a loudspeaker. The produced sound has subtly fine musical results with a sense of many different tone sources as in an individual-oscillator system instrument.

ELECTRONIC MUSICAL INSTRUMENT

This is a continuation of application Ser. No. 115,646, filed Feb. 16, 1971, now abandoned.

BACKGROUND OF THE INVENTION

In most of the keyboard electronic musical instruments, every key causes a plurality of keyers to operate for respectively switching the tone signals having frequencies in a harmonic relation with each other, some for obtaining an attack effect, and some for combining partials into a complex voice. However, in case of the instruments with tone generators of frequency divider systems, the resultant effects are not very satisfactory. All the octavely related tone signals are locked together in frequency and phase. A conventional attack keyer which switches a tone signal with an envelope having an abrupt build-up to its peak amplitude upon depression of the associated key and a subsequent decay is provided in order to eliminate the monotony of a lasting organ tone keyed by a normal tone keyer, to increase a special performance effect, and to produce sounds which are very similar to sounds produced from a natural musical instrument. In general, the attack tone keyer switches a tone signal of an 8', 5 1/3', 4', 2 2/3', 2' or 1 3/5' foot register note, while the normal tone keyer switches 8-foot register note. That is, the attack signal has a frequency which is harmonically related with the normally keyed signal. However, in an electronic organ of a frequency divider system, those tone signals have their own fixed (locked) frequencies at all the times. In other words, the pitch (frequency) and the amplitude of the tone never fluctuate by the slightest amount at the beginning of the tone sounding as would be found in performance of the natural musical instrument. Therefore, it has been impossible for the conventional electronic musical instrument to eliminate such monotony.

Furthermore, as shown in FIG. 1, in the conventional keyboard electronic musical instrument, with square wave frequency divider tone generators, a fundamental frequency tone signal and a second harmonic tone signal are fed from square wave tone generators G to a mixing circuit MIX through tone keyers E₁ and E₂, respectively. These tone signals are mixed in the mixing circuit MIX, in such a manner that the level of the second harmonic signal is 1/2 of that of the fundamental signal when the tone keyers E₁ and E₂ are opened (conductive) in association with the operation of a corresponding key in the keyboard K thereby to obtain a stepped wave used to compensate for a disadvantage of the square wave tone generator system, namely, the shortage of even-harmonics. Further, this stepped wave is tone colored through a filter circuit F to a loud-speaker SP.

However, in such a conventional frequency divider system, phases and frequencies of the mixed even-harmonics signals are locked with respect to the mixed fundamental signal. Therefore, the conventional electronic musical instrument has drawbacks that nothing but monotonous sounds is obtained and the sound produced is poor in natural sound sensation.

SUMMARY OF THE INVENTION

It is accordingly a primary object of the present invention to provide a novel organization of a keyboard electronic musical instrument having tone generators of frequency divider systems in which a mixed tone sig-

nal is rich in natural sound sense, whereby all of the above described drawbacks of the conventional system can be eliminated.

Another object of the present invention is to provide an electronic musical instrument, in which a fine sound effect rich in natural sound sensation can be obtained by slightly deviating a tonepitch in a part of the envelope of a composed output signal.

A further object of the present invention is to provide an electronic musical instrument which is capable of producing the same sound as that of a natural musical instrument, by accompanying a deviation in frequency and a variation in amplitude at the beginning of a sound production.

A still further object of the present invention is to provide an electronic musical instrument, wherein a sound which is more intricate and richer in natural sound sensation than that produced by utilizing a conventional sound source, can be obtained in spite of utilization of a square wave sound source.

The foregoing objects and other objects as well as the characteristic features of the invention will become more apparent from the following detailed description and the appended claims when read in conjunction with the accompanying drawings, in which like parts are designated by like reference symbols.

BRIEF DESCRIPTION OF THE DRAWING

In the accompanying drawings:

FIG. 1 is a block diagram showing an example of the conventional keyboard electronic musical instruments,

FIG. 2 is a block diagram illustrating an embodiment of the keyboard electronic musical instrument according to the present invention,

FIG. 3 is a block diagram showing an example of the frequency shifter utilized in the present invention,

FIG. 4 is a graphic diagram showing envelopes of output signals furnished from a device shown in FIG. 2,

FIG. 5 is a block diagram of another embodiment according to the present invention,

FIG. 6 is a block diagram illustrating a further embodiment of the present invention,

FIG. 7 is a block diagram of a still further embodiment of the present invention,

FIG. 8 is a block diagram showing an example of the frequency shifter shown in FIG. 7, and

FIG. 9 is a graphic diagram illustrating each of harmonic components and its level of an output signal of the device shown in FIG. 7.

DETAILED DESCRIPTION OF THE INVENTION

An electronic musical instrument of one embodiment shown in FIG. 2, according to the present invention, comprises tone generators G, a normal tone keyer E_N and a conventional attack tone keyer E_A which are respectively controlled by a key in a keyboard K, a frequency shifter M which deviates (shifts) the frequency of an input signal slightly higher or lower, a tone-coloring filter circuit F for a signal from the normal tone keyer, a tone-coloring filter circuit F_A for a signal from the attack tone keyer, tone volume controlling devices TV, and a resistor R which serves to directly introduce a signal of the attack tone keyer to the filter circuit F_A. For each playing key of the keyboard, a plurality of tone keyers E_N and E_A would be provided in accordance with conventional keyboard format, although

for purposes of this description, only a single tone keyer pair coupled to a single key of the keyboard has been shown so as to preserve clarity.

In the above-mentioned frequency shifter M, a circuit of a single side-band modulation system is employed, for instance, as shown in FIG. 3 wherein two modulating signals different by 90° in phase are obtained by letting an input tone signal pass through a 90-degree phase difference network PS. Two extremely low frequency signals which are to be modulated (as carrier waves) and are different by 90° in phase are obtained from an extremely low frequency oscillator LFO. These modulating signals and carrier signals are respectively combined and amplitude-modulated in the modulator M1 and M2, respectively, thereby to obtain both side-band signals, and the thus obtained amplitude-modulated signals are mixed. Then, one side of each side-band signal is removed by the mixing and the carrier component is removed by a high-pass filter circuit HPF thereby to obtain a signal in which a frequency of the input tone signal is deviated higher or lower by as much as the extremely low frequency of the carrier signal.

Hereinafter, described is the operation of the embodiment shown in FIG. 2.

Signals from the tone generators G are introduced to the respective input sides of the normal tone keyer E_N and the attack tone keyer E_A by depressing the key in the keyboard K. At this time, the tone signal from the normal tone keyer E_N appears at an output terminal OUT after having passed through the tone coloring filter circuit F and the tone volume controlling device TV without any change in frequency, while the tone signal from the attack tone keyer E_A is deviated in frequency by as much as an extremely low frequency by means of the frequency shifter M, and this signal is passed through both the tone coloring filter circuit F_A and the tone volume controlling device TV, and then is mixed with the signal from the normal tone keyer E_N . Therefore, a sound obtained immediately after the depression of the key contains mainly the signal from the attack tone keyer E_A , and is resultantly different by as much as the extremely low frequency from a frequency of a succeeding lasting sound part. Thereafter the frequency (tone-pitch) of the mixed signal shifts gradually to that of the lasting sound within increment of the level of a lasting sound. This is illustrated in FIG. 4, which comprises an envelope A of the lasting sound signal from the normal tone keyer E_N and an envelope B with an abrupt build-up and a subsequent decay of an attack sound signal from the attack tone keyer E_A . As is apparent from FIG. 4, a composition ratio of the two signals different in tone pitch is varied with time. Accordingly, a recognized tone pitch varies from a point where a sound production starts till a point represented by reference symbol P, resulting in that the sound which is heard as if it is vibrate-effected or frequency-modulated can be obtained. Then after a lasting sound of a regular pitch is heard.

Now, in this arrangement, if a frequency of the attack signal is slightly shifted higher, there can be obtained a tone pitch shifting effect as is found in building-up of a sound of a string musical instrument and the like. Furthermore, the circuit may be designed so as to apply also an attack signal of the non-shifted tone pitch by connecting a circuit of the resistor R shown by a dotted line in FIG. 2.

FIG. 5 shows a circuit in which the frequency shifter M is provided in a normal tone signal path. The operation and effect of the circuit are relatively the same as those of the case described above. Furthermore, frequency shifters whose deviation frequencies are different from each other may be provided in both of the tone signal paths.

FIG. 6 illustrates a circuit which is often utilized in the case of a square wave tone generators. In this circuit, a normal tone keyer E_{N4} of a 4-foot tone signal is provided in addition to a tone keyer E_{N8} of an 8-foot tone signal, and a frequency shifter M_n is connected to the output side of the tone keyer E_{N4} thereby to deviate a frequency of the signal of the 4-foot register. In this circuit, the signal of the 4' register is adapted to compensate for even-harmonics with respect to a fundamental wave of the fundamental tone signal of the 8' register, and the frequency shifter M_n serves to deviate a phase and a frequency of a signal of the 4' register with respect to the fundamental wave thereby to increase a natural sound sensation. On the other hand, a frequency shifter M_a provided in the output side of an attack tone keyer E_A is adapted for slightly deviating a part of frequencies during the envelope of a combined output signal. The operation and effect of this circuit (attack signal path) are the same as those in the above-mentioned case.

An electronic musical instrument of the embodiment shown in FIG. 7, according to the present invention, comprises square wave tone generators G, tone keyers E1 (for the 8-foot signal) and E2 (the 4-foot signal) each of which is controlled by a key in the keyboard K, a frequency shifter M in the output signal path from the tone keyer E2, a mixing circuit MIX, a variable resistor VR which serves to directly introduce (by-pass) a signal from the tone keyer E2 to the mixing circuit MIX with its level adjustable, a filter circuit F for tone-coloring, an amplifier AMP and a loudspeaker SP. The 4-foot register tone signal has a frequency which is an octave higher than that of the 8-foot register tone signal.

The arrangement of the frequency shifter M in FIG. 7 may be of either a system obtaining a so-called single sideband or a system obtaining a double side-band. However, explained herein is the system to obtain a single side-band utilizing a modulator and a demodulator as illustrated in FIG. 8.

As is shown in FIG. 8, the frequency shifter comprises a balanced modulator BM, a band pass filter BPF, a single side-band demodulator DM, a high frequency oscillator LO_1 whose oscillating frequency is f_1 , and another high frequency oscillator LO_2 whose oscillating frequency is f_2 . The twice frequency or 4-foot signal (frequency f_s) serves to balance-modulate a signal (frequency f_1 , e.g. 50 kHz) furnished from the oscillator LO_1 in the balanced modulator BM. Therefore, the output of the balanced modulator BM involves both side-band components consisting of frequencies $(f_1 + f_s)$ and $(f_1 - f_s)$, then, one of the two side band components, namely, $(f_1 - f_s)$ is eliminated out of the output by means of the band pass filter BPF, and the other of the two side-band components, namely, $(f_1 + f_s)$ is fed to the demodulator DM. The demodulator DM demodulates the signal of the frequency component $(f_1 + f_s)$ with the reference frequency $f_2 = f_1 + \Delta f$ (where Δf is an extremely low frequency, 0.5 to 10 Hz) furnished from the oscillator LO_2 whose oscillating frequency is slightly

defferent from that of the oscillator LO₁. Therefore a signal whose frequency is $f_s - \Delta f = (f_1 + f_s) - (f_1 + \Delta f)$, is obtained as an output of the demodulator DM. This signal is a signal which is obtained by, deviating the frequency of the 4-foot signal lower by as much as Δf . Thus, the 4-foot signal is slightly deviated, in frequency, and the thus deviated 4-foot signal is mixed with the 8-foot signal at a level of about 1/2 with respect to that of the 8-foot tone signal thereby to obtain a complex tone signal. Furthermore, the mixed complex tone signal may be formed by the following steps that, while the 4-foot signal being applied to the frequency shifter M, the 4-foot signal is also passed through a variable resistor VR as shown by a dotted line in FIG. 7, thereby to obtain a signal with no frequency deviation, and the latter signal is also mixed with the 8-foot tone signal. It is shown in FIG. 9, that all the harmonics, of the 4-foot signal, whose degrees (2, 6, 10, ...) are even-numbered times those (1, 3, 5, 7, 9, ...) of the 8-foot signal are each deviated by as much as the frequency Δf .

Herein before, a case where the 4-foot signal is frequency deviated by as much as the extremely low frequency Δf , has been described. However, in this case the fourth, the eighth and the twelfth harmonics are not present. Therefore, in case of forming a complex tone signal by mixing the 2-foot signal and the 1-foot signal, if these footage signals are made to be mixed after having passed through the frequency shifters which serve to deviate the respective harmonics by Δf in frequency, it will bring a more effective result. In addition, if the quantities of frequency deviation with respect to the harmonics are made to be a little different from each other, it will be much more effective.

The quantity of frequency deviation should be within a range from 0.5 Hz to 10 Hz for a fine result in operation, whichever the frequency is deviated higher or lower. When the quantity of frequency deviation is approximately within a range from 5 Hz to 7 Hz it pro-

duces an outstanding effect in a musical performance. For a relatively quick tempo music, and within a range from 0.5 Hz to 2 Hz for a slow tempo music such as a church music.

While a few embodiments of the present invention have been illustrated and described in detail, it is particularly understood that the invention is not limited thereto or thereby.

I claim:

1. An electronic musical instrument comprising, in combination, a tone generator means of a frequency divider system for providing a plurality of tone signals including harmonically related ones, a keyboard having playing keys, a plurality of controllable tone keyers provided for each respective playing key of said keyboard, said keyers being connected to said tone generator means and coupled to said respective playing key for control thereby, each said tone keyer respectively gating a tone signal from said tone generator means which has a frequency harmonically related with each other gated tone signal, at least one frequency shifter means receiving an output of a frequency f from one of said keyers and thereby transposing the frequency of the tone signal therefrom by a constant amount, a mixing circuit for mixing the output from said frequency shifter and the output from the rest of said keyers, and an electro-acoustic transducer for converting the mixed signal into sound.

2. An electronic musical instrument as defined in claim 1, in which one of said tone keyers is an attack tone keyer for providing an envelope for the respective tone signal which has an abrupt build-up and a subsequent decay.

3. An electronic musical instrument according to claim 1 in which said tone generators are square wave signal generators and said plurality of tone keyers provided per key respectively switch tone signals having frequencies octavely related with each other.
